ATTORNEY

UNITED STATES PATENT OFFICE.

WALTER F. WARE, OF HADDONFIELD, NEW JERSEY, ASSIGNOR TO THE WALTER F. WARE COMPANY, A CORPORATION OF NEW JERSEY.

SYRINGE AND MEDICINE DROPPER.

Application filed August 12, 1927. Serial No. 212,418.

My invention relates to syringes, medicine droppers and similar apparatuses, comprising a tube or barrel of glass terminating at one end in a nozzle and provided at the other end with a compressible elastic bulb by the expansion of which a medicament may be drawn into the barrel through the nozzle thereof and by the compression of which the said liquid is expelled through the nozzle to the portion of the body to be treated therewith.

In the construction of syringes and droppers of this type or character, it has heretofore generally been considered that if the liquid came into contact with the rubber no undesirable effects would ensue, other than perhaps the difficulty or necessity of cleaning the rubber, as well as the glass, after each use of the apparatus, particularly if the device were to be used for applying different medicaments. Both glass and rubber have been generally considered to be inert with respect to many of the liquids with which such syringes or droppers are commonly used. But I have found that the sulphur used in vulcanizing rubber and some of the other ingredients composing either hard or resilient rubber form, after a time, a deposit commonly known as "bloom" on the surface of the rubber. This bloom, which is frequently composed of sulphur, readily dissolves in or floats in suspension in liquids, such as are usually employed in uretic compounds, eye washes and other medicated liquids which are used on inflamed tissues, and the sulphur and other ingredients of the rubber thus coming into contact with the diseased or inflamed tissues and surfaces produce an acute inflammation, stinging and other harmful reactions.

The main object of my invention is to provide a syringe, eye droppers and similar apparatus, comprising only a glass cylinder and a rubber bulb, but in which the liquid drawn into the cylinder or barrel is prevented from coming in any contact whatever with the rubber or with anything except the glass comprising the barrel of the device.

A further object of my invention is to provide a syringe or dropper of the class or type described, with a bulb which fits over the end of the cylinder and which is provided with rigid projections against which the operator may place his fingers, preferably the first and second fingers, and have the free use of his

thumb to compress the bulb and express or eject the liquid from the cylinder, the said projections also preventing the syringe from rolling when it is placed on a flat surface comprising any suitable support. 60

A further object of my invention is to provide a construction wherein, after the cylinder has been filled with a liquid medicament, the syringe may be inverted with the nozzle uppermost, without causing the liquid to 65 come into contact with any rubber whatever, or with any material, except the glass of which the cylinder is made.

A further object of my invention is to make the capacity or cubical contents of the compressible bulb slightly less than that of the cylinder or tube so that the cylinder will never be completely filled with the liquid by the expansion of the bulb. 70

Other objects of my invention will appear 75 in the specification and claims below.

Referring to the drawings forming a part of this application and in which the same reference characters are employed throughout the various views to designate the same parts, 80

Fig. 1 is a vertical longitudinal section of a syringe embodying my invention, showing the tube nearly filled with the liquid medicament, after the bulb has completely expanded.

Fig. 2 is a similar view of the same apparatus, inverted, with the nozzle uppermost, showing the tube nearly filled with liquid but prevented from coming into contact with anything except the glass of which the tube is made. In this figure, a part only of the bulb 85 is in section, a fragment being shown in side elevation to clearly illustrate the nature of the projections on the opposite sides of the bulb, and

Fig. 3 is a transverse section on the line 95 3—3 of Fig. 1 looking toward the bulb.

My improved syringe or medicine dropper, comprises (1) a glass barrel or tube 1 having a suitable nozzle 2 provided with a small nozzle opening 3 at one end and a glass wall 100 4 at the other end provided at its center with a small opening or perforation 5, and (2) a bulb 6 of resilient rubber having a neck 7, tightly clasping around the outside of the end of the barrel or tube 1, fitting the wall 4 and 105 preferably provided with two lugs or projections 8, 8 diametrically oppositely disposed on the bulb and providing rather rigid shoulders against which may be placed two fingers (e. g., the first and second fingers of the one 110

using the device), thus permitting him to compress the bulb 6 by pressing with his thumb against the spherical end 9 thereof to discharge the medicated liquid 10 contained in the tube or cylinder 1.

The bulb 6 forms an air-tight chamber at one end of the tube or cylinder 1, with the small opening 5 affording the only means of communication between the interior of the tube 1 and the interior of the bulb 6, and when the device is inverted with the nozzle uppermost, any liquid 10 contained in the tube 1 will not pass through the small opening or aperture 5. The liquid cannot pass through this small orifice 5 to displace the air in the bulb 6. Thus it is that the liquid 10 drawn into the tube or barrel 1 will be prevented from coming into any contact whatever with the rubber of the bulb 6 or with anything except with the glass of the tube 1.

My device, therefore, is adapted for repeated use with different medicated liquids and that with the least trouble possible, it being necessary to merely separate the bulb from the tube and wash or rinse the tube, and possible dry or wipe the glass tube to thoroughly cleanse the same, for the bulb will not have been touched or contaminated at all by the liquid which was used in the tube.

The lugs 8 are preferably so located and proportioned as to be brought into contact with any flat support on which the dropper may be placed or laid in a substantially horizontal position, for when the syringe or dropper is so placed and is rolled slightly on said surface, these projections extend into a plane 11, 11 drawn tangentially to the bulb and to the surface of the tube adjacent the nozzle 2, as indicated in the dotted line in Fig. 2. They therefore are operable to prevent the syringe or dropper from rolling off the support and falling onto the floor.

The cubical capacity of the bulb when fully extended, is a little less than that of the tube or barrel so that if the bulb be fully deflated and the nozzle 2 be dipped into a liquid and the bulb be allowed to expand by its own resiliency, the medicated liquid drawn into the tube will never rise to the end wall 4 and will, therefore, never be drawn through the aperture 5 into the bulb, and, as stated before, when the tube is filled with liquid and the device is inverted and the liquid brought into contact with the wall 4, it will never pass through the hole 5 and will, therefore, never come into contact with the rubber.

In this way the medicament which may be placed in the tube is absolutely prevented from coming into contact with the rubber bulb and the rubber bulb is never touched by the liquid; therefore, none of the materials of which the rubber bulb is composed can be dissolved or suspended in the liquid and thus carried with the liquid to an inflamed and sensitive tissue.

It is to be noted that the air passage or opening 5 through the wall 4 is located at a point remote from the neck 7 of the bulb 6 and is preferably located coaxially with the barrel or cylinder 1. This small opening is not near any rubber of the bulb 6, nor does any rubber of the bulb overlie the opening to form a flap or valve, so that in using the syringe filled with liquid, if the syringe be put into any position, whereby the liquid may contact with the wall 4, the liquid cannot come into contact with the rubber of the bulb or pass through the hole 5 in the integral wall 4, situated remote from any portion of the rubber bulb, and from the cylindrical walls of the tube or barrel 1.

It is also to be understood that the nozzle 2, which is integral with the barrel 1 may be given any suitable shape to adapt the device to any particular use.

Having thus described my invention, what I claim and desire to protect by Letters Patent of the United States is:

1. In a device of the character described, the combination of a hollow glass barrel provided with a glass nozzle at one end and an integral glass wall at the other end, and a resilient bulb tightly fitting around the outer surface of said barrel at the end thereof which is provided with said wall, said wall being provided with an aperture therethrough located substantially coaxial with said barrel and of so small a size that a liquid in said barrel will not flow through said aperture after said bulb is fully expanded and the device is thereafter inverted to bring the nozzle end of the barrel uppermost, the cubical capacity of said bulb, when fully expanded, being slightly less than that of said barrel and operative, when expanding, to draw liquid into said barrel through said nozzle and when being compressed, to eject liquid from said barrel through said nozzle.

2. In a device of the character described, the combination of a hollow glass barrel, having an integral glass nozzle at one end and an integral glass wall substantially closing the other end, said glass wall being provided with a small opening therethrough substantially coaxially positioned with said barrel and a resilient hollow rubber bulb having a neck fitting around the said closed end of said barrel and provided with a pair of projections adjacent said neck and arranged on opposite sides of the axis of said bulb forming shoulders which may be used in compressing said bulb and which prevent the device from rolling when placed on a slightly inclined surface, said bulb being operative when expanding to draw liquid into said barrel through said nozzle and when being compressed to eject liquid from said barrel through said nozzle, the cubical capacity of said bulb, when fully expanded, being less than that of said barrel, and said

opening in said wall being so small that when said bulb has fully expanded, liquid will not flow therethrough into said bulb when said device is turned up or the liquid therein to 5 contact with said wall.

3. In a device of the character described, the combination of a hollow glass barrel having one end tapered to form a nozzle and having the other end substantially closed by a 10 glass wall integral with the walls of said barrel, said glass wall being provided with a small opening therethrough positioned substantially coaxial with said barrel and a hollow rubber bulb tightly fitting around 15 the end of said barrel having said glass wall and provided with a pair of forwardly projecting lugs providing relatively ample and rigid supports for the fingers of the operator of said device, said lugs being operative 20 to prevent the device from rolling when said device is laid in a substantially horizontal position upon a plane support.

4. In a device of the character described, the combination of a hollow glass barrel having one end tapered to form an integral 25 glass nozzle and having the other end turned inwardly to provide a wall at the end of said tube having a small aperture therethrough at substantially the center thereof 30 and a resilient hollow rubber bulb fitted tightly around the closed end of said barrel and provided with finger rests near said end

of said tube and on diametrically opposite sides of said bulb adjacent said tube, said projections intersecting a plane tangent to 35 said bulb and to the nozzle end of said barrel, said bulb being operative, when expanding, to draw liquid into said barrel and when being compressed to eject liquid from said barrel through said nozzle, the cubical capacity of said bulb when fully expanded being 40 slightly less than that of said barrel.

5. In a device of the class described, the combination with a hollow generally cylindrical glass barrel having an integral tapered 45 glass nozzle at one end and a resilient hollow rubber bulb, generally circular in transverse cross-section, fitting over and around the end of said barrel opposite to that at which is said nozzle, said bulb being provided with a pair of diametrically disposed forwardly projecting lugs integral with the bulb and terminating in substantially flat ends adjacent the point of the attachment of said bulb to said barrel, said lugs projecting outwardly from opposite sides of said bulb and into and beyond a plane tangential to the nozzle end of said barrel and to the outer surface of said bulb between said lugs to prevent the device from rolling when it is placed 50 substantially horizontally on a flat surface.

In witness whereof, I have hereunto set my hand this eleventh day of August, 1927.

WALTER F. WARE.
